UNITED STATES PATENT OFFICE.

DANIEL K. WERTMAN AND WILLIAM H. REINBOLD, OF CENTRALIA, PA.

IMPROVEMENT IN MACHINES FOR GATHERING CLOVER-SEED.

Specification forming part of Letters Patent No. 58,517, dated October 2, 1866.

To all whom it may concern:

Be it known that we, DANIEL K. WERTMAN and WILLIAM H. REINBOLD, both of Centralia, in the county of Columbia, in the State of Pennsylvania, have jointly invented a new and useful Improvement in Clover-Stripping Machines; and we do hereby declare that the following is a full, clear, and exact description of the construction and operation of the same, reference being had to the annexed drawings, making a part of this specification, in which—

Figure 1 is a perspective view of the machine; Fig. 2, a plan view of the same, showing how the lever is attached to the uppers; Fig. 3, a side elevation of the same; Fig. 4, an elevation view of the upper in its connection with the axle into which the teeth are set; Fig. 5, a section view of the teeth as connected with the axle; Fig. 6, a transverse section of one of the teeth on *x x'*.

The nature of our invention consists in providing the stripping-machine with a lever, so attached to the uppers, holding the reel or fan, that it (the lever) will allow the teeth to be raised or lowered to accommodate themselves to the length of the clover to be stripped without being obliged to lower or raise the box or body itself of the machine.

To enable others skilled in the art to make and use our invention, we will proceed to describe its construction and operation.

Similar letters will refer to similar parts throughout the whole description.

We construct our machine as the already-known clover-stripping machine, and mainly composed of a main box or body, *X X*, open in front, and set on a swivel-wheel, *S*, in lieu of hind wheels, and on a set of fore wheels, *S' R*.

On axle *m* we attach a sufficient number of teeth, *a*, of a peculiar shape, as shown in Figs. 4 and 6. Said teeth are set apart as close as possible to each other, so as to allow but the width of a clover's stem to be caught between, and each tooth is made independent from the other, made as shown in Fig. 5. They set on the square of the axle *M*, there held fast by a fitting plate of iron, *K*, which is bolted tight on axle *M* by bolts *C C*, so that if during work a tooth breaks, by loosing the neighboring bolts it is easy to pull out the broken tooth, set a

new one instead, screw the bolts tight, and set to work again.

Now the axle *m* is fixed and connected with the box, *s* so that it remains (the axle) independent of the box, the sides of which are simply placed or set on top of the axle, where it remains steady, by means of notches cut in appropriate places in the sides of the box to that effect.

Now in the space between wheels *S' R* and sides of box are fastened onto the axle uppers *n*, shaped like a cross, the arms of which are placed lengthwise in the sense of the box. The front branch or arm receives and holds the axle of reel *R'*. The lower arm is fastened on axle, as aforementioned, and the upper arm receives rod *Z*, which connects both uppers together.

Now the remaining or back arm receives on both sides of box two levers, *P*, connected together on back of box by rod or handle *P'*, said levers *P* and *P'* to be made either of wood or of iron, or of any suitable metal or material.

Two pulleys, one driving, *o*, attached to wheel *S' R* on the right-hand side, and one driven, *o'*, attached on axle or reel. A belt, *B*, connects both pulleys, and when the machine goes ahead the belt drives reel.

Now it is obvious that by raising or lowering handle *P'* of lever *P*, we will act on axle *m*, and consequently on teeth set upon said axle, and lower or raise said teeth, so as to accommodate their positions to the length of clover to be stripped.

It is also visible that any movement of lever *P* does not affect in the least the respective positions of reel *R'*; that it remains constantly, as regards the set of teeth, in the same position, that the movements of the lever do not either act on box *X*, which remains constantly in proper horizontal position, whereas in other stripping-machines now in use, and on which we assert our invention to be a decided improvement, there is a lever placed crosswise on the rear of the box, which it elevates or lowers to accommodate the teeth then set on the front of the box to the length of the clover, said movement of box compelling to fix it on a heavy and costly frame on which the above-mentioned movement may be obtained as fulcrum.

Having thus described our invention, what

we claim as our invention, and desire to secure as such by Letters Patent of the United States, is—

1. The peculiar setting of teeth *a a a* on axle *m*, in the manner and for the purpose above set forth.

2. The combination of lever *P* with uppers *n*, reel *R'*, and axle *m*, when constructed and operated in the manner and for the purpose above set forth and described.

3. The independent connection of teeth and uppers and lever from body or box of machine, allowing the teeth to be worked irrespective of the box, as aforesaid set forth and described, and for the purpose mentioned.

DANIEL K. WERTMAN.
WILLIAM H. REINBOLD.
